FULL-FASHIONED STOCKING

Madison L. Dengler, Robesonia, Pa., assignor to
 Wm. F. Muller, Inc., Robesonia, Pa., a corpora-
 tion of Pennsylvania

Application February 28, 1938, Serial No. 193,049

3 Claims. (Cl. 66—172)

This invention relates to hosiery, and particularly to flat knit or full-fashioned hosiery.

In the knitting of full-fashioned hosiery, many expedients have been advanced for creating run stops. It is a well known fact that unless the leg of the stocking is, in some manner, snagged, the majority of runs commence at the upper part of the stocking, and usually in the area fastened into the garters of the wearer. This is enhanced by the fact that women are oftentimes careless in attaching garters to the stocking, and do not always place the garters on the welt. To aid in the elimination of runs, it is customary to make that part of the stocking called the "after welt" out of the same kind of heavier material that the welt portion of the stock is made of, and is usually heavier than that material of which the leg portion is produced. In some instances, the area below the welt and usually above the knee of the wearer is provided with one or more transfer courses, which are more or less effective in stopping runs which commence above the same.

If, however, one of the threads above the transfer courses becomes broken, through the pull of the garter or otherwise, the run may continue right on through these transfer courses, and oftentimes extend through the full length of the stocking.

The primary object of the present invention is to provide an effective run stop.

A further object of the invention is to beautify the stocking by providing therein courses which simulate a purl stitch.

According to the invention, a stocking having a welt is provided beneath the welt with a plurality of regular knit courses, a reinforcing thread is then introduced and the regular knitting continued for one or more courses, a plurality of transfer courses are then made with the reinforcing thread included, one or more courses of regular knitting with the reinforcing thread included is then knit, and then the balance of the stocking is knit in the conventional manner. In stockings, having a heavy after welt, the reinforcing thread is an additional reinforcement in the course area through which it extends. There may be either a single transfer course, or a plurality of such courses in this reinforcing thread area.

The drawing illustrates an embodiment of the invention, and the views therein are as follows:—

Figure 1 is a side view of the stocking with the reinforcing thread area and transfer courses exaggerated.

Figure 2 is an enlarged fragmentary view showing the knitting.

Figure 3 is an enlarged fragmentary view of the upper part of the stocking with the reinforcing thread area and transfer courses exaggerated, and

Figure 4 is a view similar to Figure 2 on a reduced scale, and shows adjacent transfer courses.

As illustrated in the drawing, the stocking A has a welt B, and in the present instance, is shown with an after welt C. At a suitable point in the after welt, the stocking is provided with an extra reinforcing thread D, which extends for a number of courses, to provide a reinforcing thread area E. Intermediate this reinforcing thread area, there is a plurality of transfer courses F. In the present instance, there are shown two transfer courses F¹ and F². Below the point G, indicating the bottom of the after welt, the leg H, including the instep I and reinforced heel J and reinforced sole K are knit in the conventional manner.

Figure 2 indicates, in the present instance, the knitting in the after welt, the courses M representing reinforced threads, such as are customarily used in providing the after welt. In this respect, it is not intended that there shall be any limitation with respect to this after welt when used, nor is it intended that an after welt shall always be included in connection with the invention. Suffice to say, that, for the purpose of describing the invention, it will be considered that there is an after welt below the welt of the stocking, although the invention may be embodied in a stocking which has no after welt.

The courses indicated by the letter D are intended as regular knit courses with a reinforcing thread added to the type of thread which is used in the courses M. In the present instance, there has been shown four regularly knit courses including the reinforcing thread, then a transfer course F¹, then a regularly knit course D, then a transfer course F², and then four regularly knit courses, including the splice thread E, while the courses M below the same are regularly knit courses of the reinforced after welt with the reinforcing thread withdrawn.

In Figure 4, the regularly knit course D between the transfer courses has been omitted, so that the transfer courses are adjacent.

In Figures 1 and 3, there has been an attempt to illustrate an unusual condition which results from the introduction of the reinforcing thread with the plurality of transfer courses in the area thereof. The transfer courses including the in-

termidate regular course appear to bulge out forming a ridge which simulates a purl stitch, and adds considerable to the aesthetic beauty of the stocking. This particular feature, therefore, is adaptable to articles other than hosiery, the same being produced by introducing a reinforcing thread area with a plurality of transfer courses intermediate thereof, and having the transfer courses either adjacent or separated, and one or more regular knit courses between the same.

It has been found, by many experiments and tests, that runs commencing above the reinforced transfer area will not pass through that area even though threads are broken above the area. The invention, therefore, fills a long felt need in connection with full-fashioned hosiery, and the inclusion of such a device into the stocking, enhances, rather than mars, the beauty of the garment itself.

Of course, the mention of numbers of courses, etc. herein has been only for purposes of description, and these are not intended as limitations because various modifications and changes may be made in the described article and method of knit-

ting the same without departing from the invention herein set forth and hereafter claimed.

The invention is hereby claimed as follows:—

1. A stocking having a regular welt and after welt with a reinforcing thread knit into two or more adjacent courses of the after welt, and having two or more substantially adjacent transfer courses in the reinforced part of said after welt whereby the transferred area will stand out from the face of the fabric. 5

2. A stocking having a regular welt and after welt with a reinforcing thread knit into two or more adjacent courses of the after welt, and having two or more succeeding transfer courses in the reinforced part of said after welt whereby the transferred area will stand out from the face of the fabric. 10

3. A stocking having a regular welt and after welt with a reinforcing thread knit into two or more adjacent courses of the after welt, and having two or more succeeding transfer courses with a regular knit course between same in the reinforced part of said after welt whereby the transferred area will stand out from the face of the fabric. 15 20
